UNITED STATES PATENT OFFICE.

LEONIDAS D. WEST, OF DENVER, COLORADO.

FUEL-SAVER AND SMOKE-CONSUMER.

1,267,296.

Specification of Letters Patent. Patented May 21, 1918.

Application filed June 12, 1917. Serial No. 174,320.

To all whom it may concern:

Be it known that I, LEONIDAS D. WEST, a citizen of the United States, residing at Denver, in the county of Denver and State of Colorado, have invented certain new and useful Improvements in Fuel-Savers and Smoke-Consumers; and I do declare the following to be a full, clear, and exact description of the invention, such as will enable others skilled in the art to which it appertains to make and use the same.

My invention relates to those devices intended to augment combustion by the injection of a restricted quantity of highly heated air or other fluid into the combustion chambers or other suitable parts of cook stoves, ranges, small furnaces, water heaters, and analogous fuel burning means.

The principal object of the invention is to provide a device of the class described which may be easily and inexpensively manufactured and marketed, and readily applied to numerous types of stoves, ranges and the like, without making any alterations whatever in the construction thereof, and with this general object in view, the invention resides in the novel features of construction to be hereinafter fully described and claimed, the descriptive matter being supplemented by the accompanying drawings which form a part of this specification and in which:

Figure 1 is a longitudinal section of one form of the invention showing the same applied to the door of a small furnace or water heater;

Fig. 2 is a transverse section on the plane of the line 2—2 of Fig. 1;

Fig. 3 is a front elevation of a range with parts broken away to show the application of the invention thereto; and

Fig. 4 is a vertical transverse section on the plane of the line 4—4 of Fig. 3.

In the drawings above briefly described, the numerals 1 and 1^a designate a pair of elongated hollow bodies formed of cast iron, steel or any other suitable material. In fact, these devices could well be formed of fire clay should occasion demand. The body 1 is of cylindrical shape and is adapted for application upon small furnaces or water heating devices as shown in Fig. 1, whereas the body 1^a is comparatively flat, being of substantially oval shape in transverse section, this type of the device being intended principally for use in the upper flues of

cook stoves and ranges such as that illustrated in Fig. 3. For applying the device as shown in Fig. 1, a fluid supply pipe 2 will pass through the door 3 with the inner side of which the adjacent end of the body 1 contacts, the outer end of said pipe being provided with a suitable pipe connection 4 which is threaded into tight contact with the outer side of the door to hold the device in operative position thereon. The connection 4 is shown provided with a suitable type of plug valve 5 whereby the amount of air passing therethrough may be readily controlled. If steam, oil, or the like is to be passed through the pipe 2 into the body 1, another type of valve will necessarily be employed, but since the appropriate types are well known to those skilled in the art, further explanation and detailed description need not be given.

When the invention is applied as illustrated in Fig. 3, a comparatively long fluid supply pipe 2 leads from the exterior of the stove or range to the hollow body 1^a, the outer end of said pipe being provided with a plug valve 5^a and with a pet cock 5^b as illustrated in the drawings. Both types of the invention employ a substantially semi-circular fluid spraying head 6 which is provided with a tubular perforated neck 7 extending through an opening in one end of the body into the interior of said body. It will be observed that the neck 7 is of considerably less size than the body 1 or 1^a with which it coöperates, said neck therefore serving to choke down the rush of air through the drum so that the latter serves as an effective means for heating such air, after which heating it is discharged through the neck into the head 6 and is sprayed from the latter through a plurality of fine perforations 8 therein. The air or other fluid, when discharged in this manner, mixes thoroughly with the flames and hot gases in the stove, furnace or the like, and greatly increases combustion. By so augmenting combustion, the accumulation of soot and carbon is reduced to a minimum and since all of this usually waste material is consumed, less fuel is required to produce the same amount of work.

Numerous modifications of the invention may be made within the scope of the appended claims, but the essentials remain the same, that is a hollow drum, a pipe for supplying a fluid to one end of said drum, and

a spraying head having a neck extending into the drum through the other end thereof, said neck having perforations and being preferably closed at its inner end. Both types of the invention are highly efficient for the purposes intended and on account of the advantages of the features of construction shown and described, such features constitute the preferred form of the device. It is to be understood, however, that within the scope of the invention as claimed, numerous minor changes may be made as above suggested.

Claim:

1. A fluid supply device for stoves and furnaces comprising an elongated hollow fluid-heating body adapted to be exposed to the heat from the fire box, one end wall of said body having a central opening for the attachment of a fluid supply pipe, the other end wall of said body also having a central opening, a fluid spraying nozzle adjacent said last named end of said body and on the exterior thereof, and a tubular inlet neck extending from said nozzle into said body

through said last named opening, said neck having perforations positioned in said body.

2. A fluid supply device for stoves and furnaces comprising an elongated one-piece hollow fluid-heating body adapted to be exposed to the heat from the fire box, one end wall of said body having a central opening for the attachment of a fluid supply pipe and the other end wall of said body having an integral hollow boss extending outwardly, a fluid spray nozzle on the exterior of said body and having an integral neck extending into the same through said hollow boss, said neck having a closed inner end and having perforations located in said body, and a set screw threaded through said boss for securing said neck in place.

In testimony whereof I have hereunto set my hand in the presence of two subscribing witnesses.

LEONIDAS D. WEST.
